KEY CASE

Martin Steinberger, 17 Runyon Ave., Somerset, N.J.

Filed June 23, 1964, Ser. No. 80,531

Term of patent 14 years

(Cl. D87—3)

FIG. 1

FIG. 2

FIG. 4

FIG. 3

FIGURE 1 is a front elevational view of a key case showing my new design, with the key chain in extended position;

FIGURE 2 is a similar view, but showing the key chain retracted;

FIGURE 3 is a rear elevational view thereof; and

FIGURE 4 is a bottom plan view thereof.

A key is shown in broken lines in FIGURE 1 for illustrative purposes only.

The characteristic features of my design reside in the combination, on the key case shown, of two eyelets in the upper end, a single dome-like button at the lower end, and a bead chain passing through said eyelets and co-acting with said button, all as shown.

This application is a continuation-in-part of my earlier-filed co-pending application Serial Number D. 76,506, filed September 6, 1963, and now abandoned.

I claim:

The ornamental design for a key case, as shown and described.
